Drawing of prior art Non-Adjustable Joint.

Primary Examiner—Catherine E. Kemper
Attorney, Agent, or Firm—W. Scott Carson

[57] CLAIM

The ornamental design for a adjustable joint for a knee brace, as shown and described.

DESCRIPTION

FIG. 1 is a perspective view of a adjustable joint for a knee brace showing our new design;

FIG. 2 is a front elevational view thereof;

FIG. 3 is a right side elevational view thereof taken along line 3—3 of FIG. 2;

FIG. 4 is a left side elevational view thereof taken along line 4—4 of FIG. 2;

FIG. 5 is a rear elevational view thereof taken along line 5—5 of FIG. 2;

FIG. 6 is a top plan view thereof taken along line 6—6 of FIG. 2;

FIG. 7 is a bottom plan view thereof taken along line 7—7 of FIG. 2;

The broken line disclosure of a knee brace in FIG. 1 is for illustrative purposes only and forms no part of the claimed design.
